EDWIN R. STORM, OF NEW YORK, N. Y.

ADJUSTABLE PRINTING-PLATE HOLDER.

1,095,150.

Specification of Letters Patent. Patented Apr. 28, 1914.

Application filed August 29, 1908. Serial No. 450,824.

To all whom it may concern:

Be it known that I, EDWIN R. STORM, a citizen of the United States, residing at New York, in the county of New York and State of New York, have invented certain new and useful Improvements in Adjustable Printing-Plate Holders, of which the following is a specification.

This invention relates to improvements in holders for printing-plates in which plate-clamps are used in conjunction with grooved blocks; and the objects of my invention are, first, to provide a plate-clamp having a portion that may be inserted at any point of the groove and be quickly and reliably secured thereto; second, to provide a plate-clamp having a portion that will accurately move the printing-plate any small distance to bring it to perfect register; third, to provide a plate to cover the grooves and prevent the printing-plate from denting or being forced into the grooves; fourth, to provide a plate-clamp that will hold the printing-plate and the intermediate-plate to the grooved block when a sufficient number of the clamps have been inserted in the grooves and have had their holding edges brought to bear on the edges of the printing-plate; fifth, to provide a means for removing the plates after printing; and, sixth, to provide a means of readily removing the plate-clamps from the groove. I attain these objects by means of the devices illustrated in the accompanying drawings, in which—

Figure 1 is a top view of a portion of a grooved block with a printing-plate and an intermediate-plate thereon and a plate-clamp in position in one of the grooves, the printing-plate and the intermediate-plate being broken away over that portion of the plate-clamp which is secured within the groove. Fig. 2 is a side view of the base-piece, showing the formed end adapted to be secured in the groove and the extended portion containing the threaded hole. Fig. 3 is a top view of the base-piece showing the formed end, the extended portion, the hole for the set-screw and the slot in the formed end. Fig. 4 is an end view showing the extended portion and the threaded hole therein, also the relative eccentricity of the extended end to the formed end. Fig. 5 is an end view showing the contour of the formed end and the slot therein. Fig. 6 is a side view of the adjusting-screw, showing the threaded portion, the cylindrical portion

of reduced diameter and the slotted head. Fig. 7 is a sectional view of a plate-clamp secured within a groove, showing the set-screw bearing against the bottom of the groove, the slot in the base-piece, the threaded hole in the extended portion, the adjusting-screw in the threaded hole, the face-piece having a portion working on the face of the grooved block and a portion extending within the groove engaging with the head of the adjusting-screw and the operating-tool in position. Fig. 8 is an end view of the groove, showing the adjusting screw in place within the groove, a face-piece on the grooved block and the form of the portion extending within the groove and passing over the cylindrical portion of the adjusting-screw. Fig. 9 is an end view of a groove, showing a face-piece on the grooved block, and the form of the portion extending within the groove and engaging with the head of the adjusting-screw. Fig. 10 is a view of a face-piece, showing the portion having the holding edge and the portion that extends within the groove. Fig. 11 is a perspective view of a face-piece, showing the portion that rests on the face of the grooved block and bears against the edge of the printing-plate, the portion that extends within the groove, and the hole through which is passed the operating tool. Fig. 12 is a view of the operating tool, showing the cylindrical portion adapted to work within the hole in the face-piece and the reduced portion adapted to engage with the slot in the end of the adjusting-screw. Fig. 13 is an end view of the operating tool showing the rounded edges of the reduced portion. Fig. 14 is a modified form in which the base-piece is formed integrally with a grooved block that may be locked in conjunction with other blocks in a printer's chase.

Similar numbers of reference indicate corresponding parts throughout the several views.

The block 1, of any desired size, is of the same construction as is now in common use and consists of a block having grooves 2 of greater width at the lower than at the upper part. The printing-plate 3 is placed upon the intermediate-plate 3^a, as indicated in Fig. 1. The thin intermediate-plate 3^a is made approximately the size and shape of the printing-plate. Being but slightly smaller, and lying immediately upon the

grooved block 1, it covers those parts of the grooves which lie under the printing-plate 3 and supports the printing-plate. The printing-plate 3 and the intermediate-plate 5 3^a are held to the block 1 by the plate-clamps, which consist of a base-piece 4, a set-screw 5, an adjusting-screw 6, and a face-piece 7.

The base-piece 4 is formed of a thickness 10 slightly less than the top width of the groove 2 so that when held with its top surface 8 perpendicular to the top surface of the block 1 it may be passed within the groove 2, and is formed of an outline, or section, that will 15 permit of its being rotated within the groove and secured therein, as indicated in Fig. 5. In the base-piece 4 is formed the threaded hole 9, the slot 10, and the threaded hole 11 (shown in Figs. 1, 2, 3, 4, 5 and 7). The 20 base-piece 4 is preferably made with a formed end having two faces, 12 and 13, adapted to fit against the sides of the groove, as shown in Fig. 5, and a cylindrical portion 14 whose diameter is no greater than 25 the thickness of the base-piece. (See Figs. 2, 3 and 4.)

To the threaded hole 9 is fitted the set-screw 5, which is formed of a length that is less than either the width or the depth 30 of the groove 2, and has its lower end 15 adapted to bear against and, if need be, indent the bottom surface of the groove, as indicated in Figs. 1 and 7. To the threaded hole 11, which is formed with its axis parallel to but at a distance from the longitudinal axis of the base-piece, is fitted the threaded portion 16 of the adjusting-screw 6. The adjusting-screw 6 is formed with a threaded portion 16, a cylindrical portion 40 6, adapted to pass within the threaded hole 11 and a head 17 in which is formed the slot 18. Between the head 17 and the cylindrical portion 6 is formed the shoulder 19. (See Figs. 6 and 7.)

45 To the cylindrical portion 6 of the adjusting-screw is fitted the curved surface 20 of the member 21 which is formed integrally with the face-piece 7. The member 21 is adapted to extend within the groove 2, and 50 is formed with a face 22 conforming with and adapted to bear against a side of the said groove 2. (See Figs. 8, 9, 10 and 11.) The member 21 is recessed, forming a surface 23, adapted to receive the shoulder 19, and a surface 24 adapted to receive the head 17, and is further formed with a surface 25, 55 tangent to the curved surface 20 and approximately parallel to the surface 22, adapted to pass the cylindrical portion of the adjusting-screw 6 when the said adjusting-screw is in the groove and the face-piece 60 is being placed in position on the block 1. (See Figs. 7, 9, 10 and 11.) In the face-piece 7 is formed the hole 26 adapted to 65 permit an operating-tool to engage with the

slot 18. On the face-piece 7 is formed a holding edge 27 adapted to bear against the inclined edge of the printing-plate 3 to hold the plate to the block 1. (See Figs. 1, 7, 8, 9, 10 and 11.)

70 The operating-tool 28, fitted to any convenient handle, not shown, is of a size to fit the hole 26 and formed with a reduced portion 29, having rounded edges, adapted to enter the slot 18 and operate the adjusting screw 6. (See Figs. 12 and 13.)

75 The manner of using the printing-plate holders is as follows: Having determined the approximate position of a printing-plate 3 upon the grooved block 1, the printing-plate is laid to one side and the base-pieces 4 with the set-screw 5 wholly within the threaded hole 9, that is, so neither extremity projects beyond the top or bottom surface of the base-piece, and the adjusting-screw 6 80 held in the threaded hole 11 are entered within the grooves, preferably in the space 85 that is to be covered by the printing-plate. To enter the base-piece 4 within the groove 2, hold the base-piece so the slot 10 is parallel 90 with the face of the block 1, and drop the base-piece in the groove, next, rotate the base-piece within the groove, this may be done by pressure of the fingers moved at a right angle to the groove, or, by inserting 95 the end of the operating-tool 28, or of a screw driver, in the slot 10 and, while holding the finger against the end of the extended portion 14, turning the operating-tool until the slot 10 is perpendicular to the bottom surface of the groove 2 and the head 100 of the set-screw 5 is exposed to view. The base-piece will then be wholly within the groove 2 and ready to be secured to place. To secure the base-piece 4 to the groove, rotate the set-screw 5 until its lower extremity 105 15 pressing against the bottom surface of the groove 2 lifts the base-piece 4 and presses the surfaces 12 and 13 against the sides of the groove with sufficient force to hold the 110 base-piece immovably to the block 1, if necessary, causing the end 15 to indent the bottom of the groove 2. When the base-piece is secured within the groove the adjusting-screw is rotated until all of the cylindrical 115 portion 6 is exposed and the face-piece 7 is put in place on the block by inserting the member 21 within the groove in the space lying between the threaded end 16 and the shoulder 19 of the adjusting-screw 6, with 120 the surface 22 bearing and sliding against a side of the groove and the surface 25 passing between the same side of the groove and the cylindrical portion 6, until the surface 20 rests on the cylindrical portion 6 and 125 the face-piece 7 rests on the top surface of the block 1. The face-piece 7 is then moved lengthwise of the groove 130 toward the head 17 causing the surface 24 to move along the cylindrical surface 130

of the head 17. The lengthwise movement of the face-piece 7 is continued until the surface 23 bears against the shoulder 19, (as shown in Fig. 7). The head of the adjusting-screw is then against one of the inclined sides of the groove 2, the member 21, with its surface 22 against the other inclined side of the groove and its surface 24 fitting against the cylindrical surface of the head 17, fills the space between the head 17 and the side of the groove. The head 17 fitting in the recessed portion of the member 21 holds it securely within the groove thus holding the face-piece 7 to the face of the block 1 but allowing it to move lengthwise of the groove. (See Fig. 9.) The hole 26 is so placed in the face-piece 7 that when the face-piece is held to the grooved block by the head 17 and the shoulder 19 bears against the surface 23, the slot 18 is accessible to the formed end 29 of the operating-tool 28, (see Fig. 7). If now the operating-tool 28 be inserted in the hole 26 with the formed end 29 engaging with the slot 18 and so moved as to rotate the adjusting-screw 6 so as to cause the threaded end 16 to be drawn farther into the threaded hole 11, the shoulder 19, bearing against the surface 23, moves the member 21 and, with it, the face-piece 7, toward the base-piece 4, or, if the movement of the operating-tool be reversed causing the threaded end 16 to be pushed farther out of the threaded hole 11, the head 17 pushes the cylindrical portion of the operating-tool bearing against the hole 26 carries the face-piece 7 along with it, thus moving the face-piece away from the base-piece 4. Having secured a sufficient number of plate-clamps within the grooves 2, with the face-pieces approximately in position the intermediate-plate 3^a, slightly smaller than the printing-plate, is placed upon the block 1; the printing-plate 3 upon the intermediate-plate 3^a, the operating-tool 28 inserted successively in the hole 26 of each plate-clamp and moved in such manner as to rotate the adjusting-screw 6 so as to draw the face-piece toward the base-piece until the holding-edge 27 bears against the beveled edge of the printing-plate 3. When each of the face-pieces have been so moved as to bring the holding-edge to bear against the beveled edge of the printing-plate 3, the printing-plate will be securely held to the block 1. (See Fig. 1.) To adjust the printing-plate upon the block, it will only be necessary to note the direction toward which the plate should be moved and the distance required to bring it to register, when the clamps along the side and end toward which the printing-plate should be moved may be loosened by unscrewing the adjusting-screws the required distance. Then by moving the face-pieces on the opposite sides the required distance forward by prop-

erly rotating the adjusting-screws the required number of revolutions or fraction of a complete revolution, the printing-plate will be moved quickly and accurately to register and securely held to place on the grooved block by the pressure of the holding-edges against the beveled edges of the printing-plate.

In Fig. 14 I have shown a modified form of the plate-clamp in which the grooved block 30, adapted to be locked with other blocks in a printer's chase to form a bed upon which a printing-plate or printing-plates may be placed, is formed integrally with the base-piece, the groove 31 being adapted to retain the member 32 of the face-piece 33 and the head 34 of the adjusting-screw 35. The threaded end 36 of the adjusting-screw 35 works in the threaded hole 37. As the block contains but one face-piece, which may be entered from the end of the groove, any form of groove that is convenient may be used and the member 32 may have its form modified as required to enable it to slide within the groove. Also a collar 38 may be formed upon the adjusting-screw 35 to bear against the member 32 and thrust, or move, the face-piece 33 away from the threaded hole 37 when the adjusting-screw is properly rotated.

Having described my invention I claim and desire to secure by Letters Patent:—

1. In a holder for printing-plates the combination of a block having grooves adapted to receive and hold one or more plate-clamps, a rigid plate adapted to be placed between the printing-plate and the grooved block, and adjustable plate-clamps held in the grooves, each of said plate-clamps consisting of a base-piece adapted to be rotated in the grooves, a set-screw working in the base-piece adapted to hold the base-piece to a fixed position, a face-piece and an adjusting-screw connecting the face-piece to the base-piece adapted to move the face-piece and the printing-plate over limited distances and to hold the face-piece, the printing-plate and the rigid plate securely to the block at any point of such limited distances.
2. In a holder for printing-plates the combination of a block having grooves adapted to receive and hold one or more plate-clamps, a rigid plate adapted to be placed beneath the printing-plate and cover the grooves under the said printing-plate, a base-piece adapted to be rotated and inserted in any one of the grooves; a set-screw adapted to hold the base-piece within the groove, an adjusting-screw held by the base-piece, and a face-piece controlled by and moving with the adjusting screw.
3. In a holder for printing-plates the combination of a block having grooves adapted to receive one or more plate-clamps, a base-piece adapted to be inserted at any point of

the groove and rotated therein a set screw adapted to hold the base-piece securely to any point of the groove, an adjusting-screw engaging with the base-piece and a face-piece with a holding edge thereon, controlled by the adjusting-screw.

4. In a holder for printing-plates the combination of a grooved block; a base-piece adapted to be inserted at any point of the groove then rotated therein; a set screw adapted to secure the base-piece rigidly within the groove; an adjusting-screw working in the base-piece; a head on the adjusting-screw; a face-piece working on the top of the grooved block; a member on the face-piece engaging with the shank and head of the adjusting-screw; a hole in the face-piece adapted to admit the passage of an operating-bar; a slot in the head of the adjusting-screw adapted to receive the end of an operating bar; and a rigid plate adapted to be placed between the printing-plate and the grooved block.

5. In a holder for printing-plates the combination of a block having grooves adapted to receive and hold one or more plate-clamps, and adjustable plate-clamps held in the grooves, each of said clamps consisting of a base-piece provided with a set-screw 30 and adapted to be rotated and held by the set-screw to a fixed position in the grooves, an adjusting-screw and a face-piece.

6. In a holder for printing-plates the combination of a block having grooves adapted to receive and hold one or more plate-clamps and adjustable plate-clamps held in the grooves, each of said clamps consisting of a base-piece provided with a set screw and adapted to be rotated and held by the set-screw to a fixed position in the grooves, a face-piece working on the surface of the grooved block and an adjusting-screw, connecting the base-piece and the face-piece adapted to move the face-piece and the printing-plate over limited distances and hold the face-piece and the printing-plate securely to the block at any point of such limited distances.

7. In a holder for printing-plates the combination of a block having grooves adapted to receive and hold one or more plate-clamps, a base-piece provided with a set-screw and adapted to be rotated and secured by the set-screw to a fixed position within one of the grooves, an adjusting-screw held by the base-piece, a member formed to extend in the groove and engage with the adjusting-screw and a face-piece formed integrally with the said member controlled by and moving with the adjusting-screw.

8. In a holder for printing-plates the combination of a block having grooves adapted to receive one or more plate-clamps, a base-piece adapted to be inserted at any point of the groove and rotated to position, a set-

screw working within the base-piece adapted to hold the base-piece securely to any point of the groove; an adjusting-screw working within the base-piece and a face-piece with a holding-edge thereon, controlled by the adjusting-screw.

9. In a holder for printing-plates the combination of a block having grooves adapted to receive and hold one or more plate-clamps and plate-clamps held in the grooves, each of said clamps having a base-piece longitudinally and transversely perforated and internally threaded and adapted to pass freely into a groove of the said block and be rotated therein, a set screw working in the transverse perforation and an adjusting-screw mounted in the longitudinal perforation.

10. In a holder for printing-plates the combination of a grooved block; a face-piece working on the surface of the grooved block; a base-piece adapted to be inserted at any point of a groove, and to be partially rotated therein; a set-screw working in the base-piece and adapted to bear on one surface of the groove; an adjusting-screw adapted to move the face-piece and the printing-plate over limited distances and to hold the face-piece and the printing-plate securely to the block at any point of such limited distances; and a member on the face-piece extending into the groove and adapted to act with the head of the adjusting-screw to hold the face-piece to position on the grooved block.

11. In a holder for printing-plates the combination of a block having grooves adapted to receive and hold one or more plate-clamps; a base-piece longitudinally and transversely perforated and internally threaded and adapted to pass freely into a groove of the said block and be rotated therein; a set-screw working in the transverse perforation adapted to fasten the base-piece in the groove; an adjusting screw held in the longitudinal perforation; a member formed to extend into the groove and engage with the adjusting screw and a movable face-piece formed integrally with the said member controlled by and moving with the adjusting screw.

12. In a holder for printing-plates the combination of a block having grooves adapted to receive one or more plate-clamps, a base-piece longitudinally and transversely perforated, having each perforation internally threaded and adapted to be inserted at any point of the groove and be rotated therein, a set-screw adapted to work in the transverse perforation and hold the base-piece securely to any point of the groove, an adjusting-screw engaging the longitudinal perforation in the base-piece and a face-piece with a holding edge thereon controlled by the adjusting-screw.

13. In a holder for printing-plates the combination of a block having grooves adapted to receive one or more plate-clamps; a face-piece working on the surface of the grooved block; a base-piece longitudinally and transversely perforated and internally threaded, and formed to permit it to pass freely into or out of the groove when held in one position and be held within the groove when partially rotated therein from the entering position; a set-screw working in the transverse perforation of the base-piece; and an adjusting-screw mounted in the said longitudinal perforation connecting the face-piece to the base-piece.
14. In a holder for printing-plates the combination of a grooved block, a face-piece working on the surface of the grooved block, a base-piece with a threaded hole therein secured within the groove, adapted to receive an adjusting-screw, an adjusting-screw working in the threaded hole, a head on the adjusting-screw adapted to pass into and work against one side of the groove, a member on the face-piece extending into the groove and adapted to pass freely to one side of the stem of the adjusting-screw in entering or leaving the groove, a wedge-shaped portion on the member extending into the groove adapted to pass between the head of the adjusting-screw and a side of the groove and act in conjunction with the head of the adjusting-screw to hold the face-piece to the grooved block, and a hole in the face-piece adapted to permit the complete rotation of an operating tool.
15. In a holder for printing-plates the combination of a grooved block, a face-piece working on the surface of the grooved block, a base-piece consisting of a single member adapted to be inserted and rotated in any one of the grooves and having two sides conforming to the sides of the groove and a longitudinal hole and a transverse perforation each internally threaded; a set screw working in the transverse perforation

and an adjusting screw working in the longitudinal hole connecting the face-piece to the base-piece.

16. In a holder for printing-plates the combination of a grooved block, a face-piece working on the surface of the grooved block, a base-piece consisting of a single member longitudinally and transversely perforated and internally threaded and formed with two sides conforming to the sides of the groove and the connecting longitudinal surfaces formed to permit rotation of the base-piece within the groove, a set-screw working in the base-piece and an adjusting-screw connecting the face-piece to the base-piece.

17. In a holder for printing-plates the combination of a grooved block, a face-piece working on the surface of the grooved block, a base-piece adapted to be inserted at any point of the groove and be rotated therein and formed with two sides conforming to the sides of the grooves of the said block and having internally threaded longitudinal and transverse perforations, a slot in one end of the base-piece adapted to receive a rotating tool, a set-screw, working within the transverse perforation and an adjusting-screw engaging with longitudinal perforation connecting the face-piece to the base-piece.

18. In a holder for printing-plates, the combination of a grooved block; a base-piece longitudinally and transversely perforated and internally threaded; and having two faces conforming to the sides of the groove, and formed to permit it to pass freely into or out of the groove when held in one position and be held within the groove when partially rotated therein from the entering position and a set-screw working in the transverse perforation adapted to hold the base-piece to a fixed position in the groove.
